UNITED STATES PATENT OFFICE

DALLAS F. GRAHAME, OF MONTREAL, QUEBEC, CANADA, ASSIGNOR TO SANFORD RILEY STOKER CORPORATION, OF WORCESTER, MASSACHUSETTS, A CORPORATION OF MASSACHUSETTS

INTERMITTENT DRIVING MECHANISM

Application filed October 11, 1924. Serial No. 743,038.

This invention relates to driving mechanisms and more particularly to a mechanism capable of rotating a shaft intermittently through variable periods of time.

5 In the operation of a stoker, it is desirable to feed coal into the combustion chamber at different rates depending upon the load being carried and the condition of the fire. It has been customary to utilize a rotary valve for the purpose of admitting steam to the engine which actuates the coal feeding ram, but such rotary valves have involved a considerable loss of steam due to leakage and have not been generally satisfactory.

10 I have found that a poppet type of valve is more satisfactory for use with the steam cylinder of a stoker ram driving engine, hence one object of my invention is to provide a mechanism capable of lifting the poppet valves automatically and at variable intervals to admit steam to the cylinder.

The stoker ram may also be suitably driven by other types of driving mechanism such as a reversing electric motor, and it is 25 accordingly a further object of my invention to provide a mechanism which may be employed to rotate any suitable controlling device, such as an electric switch of desired construction, which will cause the reciprocation of the ram as desired.

30 A further object of my invention is to provide a manually controlled automatically operated mechanism of general utility which will rotate a shaft at a uniform rate either continuously or intermittently through variable periods of time.

With these and other objects in view as will be apparent in the following disclosure, my invention resides in the combination of 35 parts set forth in the specification and covered by the claims appended hereto.

Referring to the drawings which illustrate one embodiment of my invention as applied to the operation of poppet valves for 40 controlling a steam cylinder:

Fig. 1 is a vertical front elevation, partly in section, showing one arrangement of a cam-controlled poppet valve actuating mechanism, certain parts being removed to clarify 45 the illustration;

Fig. 2 is a side elevation, partly in section, of the part shown in Fig. 1;

Fig. 3 is a section on the line 3—3 of Fig. 2 showing the poppet valve actuating mechanism;

Fig. 4 is a diagrammatic view of a stoker in which the ram is actuated by a piston in a steam cylinder;

Fig. 5 is an enlarged detail showing the cam-operating mechanism in vertical elevation;

Fig. 6 is an end view partly broken away of the handle control mechanism for the cam;

Fig. 7 is a section on the line 7—7 of Fig. 5; and

Fig. 8 is a section on the line 8—8 of Fig. 5, looking in the opposite direction from that of Fig. 7.

In accordance with the specific invention herein illustrated, I propose to rotate the shaft 10 at a uniform rate or intermittently as desired, by means of a continuously revolving driving member, connected thereto by a suitable breakable connection, such as 70 a pawl and ratchet device. The parts are so arranged that the connecting member may be permitted to remain in contact with its associated part for an indefinite period or be disconnected from and reconnected there- 75 to by a manually controlled automatically operated cam mechanism. In the construction illustrated, the power is derived from a continuously rotating worm 12 driven by any suitable means, which in turn rotates a worm gear 13 continuously in one direction. This worm gear 13 is rotatably mounted on 80 the shaft 10 and is arranged to drive the shaft through a ratchet 14 by means of a pawl 15 pivotally mounted on the side of the gear 13. The ratchet member 14 is pro- 85 vided with a single big tooth 16 and several small teeth 17 opposite thereto as shown particularly in Figs. 6 and 7.

The pawl 15 is arranged to be actuated by 90 a set of cams so that it will either engage the tooth 16 and rotate the shaft 10 continuously, or it will be caused to engage this tooth only at stated intervals and permit gear 13 to rotate once, twice or more between succes- 95 sive actuations. The cams are arranged to 100

sive rotations of the driven shaft 10. To this end, I provide two cams 20 and 21 which are arranged to lift the cam follower 22 which projects from the side of the pawl 15 over the peripheries of the cams. The cam 21 is mounted on the inside of a casing 23 in a fixed position, while the cam 20 is keyed to the shaft 24 and arranged to be rotated by the handle 25 conveniently located on the outside of the casing. It will be noted that the shaft 24 is not concentric with the shaft 10 but is located above it. The cam 20 is a disc shaped body having a circular portion 28 which will permit the pawl to contact with the ratchet teeth and rotate the shaft 10. The cam 20 also has cam surface projections 29, 30, 31 and 32 which as will be seen in Fig. 8 have cam surfaces of progressively increasing length and are intended to stop the rotation of shaft 10 for definite intervals of time of increasing duration. The cam 21 has a circular outline providing a dwell portion concentric with shaft 10 except that it is provided with a depression 34 near its bottom. A compression spring 35 is arranged to press the pawl 15 inwardly and hold the cam rider 22 against the peripheries of the two cams 20 and 21. By this arrangement I provide an effective raised cam portion or follower lifting portion of variable length, since only the part projecting above the stationary cam can affect the cam follower.

When the cam 20 is rotated by turning the handle 25 until the surface 28 is in its top-most position the projections 29, 30, 31 and 32, will be withdrawn behind the dwell portion and there will be no part of cam 20 projecting above the surface of cam 21 to any considerable extent, hence the cam rider 22 will ride around the peripheries of cams 20 and 21 and permit the pawl 15 to remain in engagement with the tooth 16 of the ratchet and thus rotate the shaft 10 at a continuous rate.

If now it is desired to rotate the shaft 10 through one revolution and then hold it stationary while the gear 13 rotates through a revolution, the cam member 20 is turned until projection 29 is at the top. Then when the cam rider 22 comes around on the surface of 21 and onto the surface of 20 and rides up over the projection 29, it will lift the pawl 15 from contact with the tooth 16 and thus permit the ratchet 14 and the shaft 10 to stop rotating. The cam rider 22 and pawl 15 go around in the direction of the arrows in Figs. 7 and 8 until the rider comes to the depression 34 at the bottom of the cam 21. This occurs when the pawl 15 is opposite one of the ratchet teeth 17 and the pawl is therefore permitted to engage one of these teeth and start rotating the ratchet 14. This movement, however, is stopped when the ratchet has moved forward the distance of one tooth, since the slot 34 is of such a length as to lift the pawl from contact with the tooth 17

after it has gone that short distance. Thereafter, the ratchet and shaft are left stationary until the cam rider 22 has come to the top and again mounted the projection 29. This time the projecting cam 29 is found to be so positioned, because of the movement ahead of one tooth length, that it will not prevent engagement of the pawl 15 with the tooth 16, whereupon the ratchet member and the shaft 10 will again rotate through a complete turn.

The lengths of the cam surfaces on the projections 29, 30, 31 and 32 are such that one, two, three and four revolutions respectively are missed by the ratchet and its shaft before the pawl and the large tooth come into engagement. That is, by turning tooth 30 to the upper position, the pawl 15 will revolve and move the ratchet member ahead one tooth, then be lifted over the tooth 16 and again engage a second ratchet tooth and move it ahead by one tooth distance. Thereafter, when the pawl 15 gets to the top, the pawl 15 will be permitted to engage the tooth 16 and give it a complete revolution. At the end of each revolution of the shaft 10, the cycle will be repeated, moving the ratchet ahead one tooth at a time.

If it is desired to stop the shaft 10 while permitting the worm gear 13 to continue rotating, one of these cams, and preferably the long cam 32, is moved to such a position that as the device continues its operation the ratchet member will be moved around until its teeth 17 are not opposite the slot 34 in the outer cam 21. Then, when the pawl 15, which has been lifted from the tooth 16 by the cam 32, gets around to the teeth 17, it cannot engage therewith, because the rider 22 is not opposite the slotted portion 34 and will not let the tooth 16 move inwardly. Therefore the pawl continues its revolution and is continuously lifted over the tooth 16 and is not able to move the ratchet member 14 forward to get into engagement with that tooth.

It will now be understood that this shaft 10 may be utilized to rotate any suitable mechanism, such as a rotary switch for controlling an electric motor, or, as illustrated, a poppet valve mechanism for admitting steam to an engine cylinder. I have illustrated in the drawings a simple type of poppet valve mechanism, although it will be understood that any other form may be used. As illustrated, the cams 40 and 41 may be keyed to the shaft 10 and arranged to actuate bifurcated levers or rocker arms 42 and 43 which are pivotally mounted independently of each other on shaft 44. They have rollers 45 and 46 on their outer ends in engagement with the cams. Each lever 42 and 43, is arranged to lift the valve actuating stems 47 and 48 at stated intervals. For this purpose, the bifurcated arms of the levers 42 and 43 have

5 pairs of sockets 49 and 50 which support two sets of pins 51 and 52 which carry the cross heads 53 and 54 to which the valve actuating rods 55 and 56 are connected. These rods have cross heads 57 and 58 at their lower ends arranged to support the valve stems 47 and 48. The stems, which are also in pairs, actuate the poppet valves 60, of usual construction, which cooperate with their seats and the steam passages to control the passage of steam to and from the steam cylinder 61 of the stoker, shown in Fig. 4, which operates the ram to feed coal from the hopper 62 through the throat 63 into the combustion chamber of the furnace.

10 15 It will be obvious that various changes may be made in this construction within the scope of my invention and the claims are to be interpreted accordingly.

20 Having thus described my invention, what I claim as new and desire to secure by Letters Patent is:

25 30 35 40 1. A driving mechanism comprising a continuously rotatable driving shaft, a rotary driven member, a pawl fastened to one member and a cooperating ratchet connected to the other, and a manually adjustable cam device including relatively adjustable cams and a cam follower connected with said pawl, said cams being so constructed that they may either provide a dwell throughout the entire cam surface and thus cause the pawl to remain in engagement with the ratchet for an indefinite period or they may provide a follower lifting portion extending above the dwell and thus remove the pawl from engagement with the ratchet at stated intervals, whereby the driven shaft may be rotated continuously or intermittently for a predetermined period of time.

45 50 55 60 2. A driving mechanism comprising driving and driven members, a ratchet connected to one member and a pawl to the other, a cam follower connected with the pawl and arranged to make and break the connection between said pawl and ratchet, and a stationary cam having a dwell portion and a movable cam having a follower lifting portion movable to an ineffective position behind the dwell portion or to an effective follower lifting position, whereby a peripheral cam surface is provided of such character that the cam follower may ride continuously therearound and cause the pawl to remain in contact with the ratchet, or the pawl will be periodically removed from contact with the ratchet and the driven member will remain substantially stationary while the driving member rotates through a complete revolution.

65 70 75 80 3. A driving mechanism comprising rotary driving and driven members, a ratchet having a large tooth and a small tooth which is connected to one member, a pawl connected to the other and arranged to drive the ratchet,

a cam follower connected to the pawl, and a cam device having a raised portion arranged to lift the pawl from contact with the large tooth and a depression permitting contact with the small tooth, said parts being so constructed and arranged that the pawl will contact with the large tooth and rotate the driven member through substantially one revolution and then be lifted from contact therewith by the follower passing over the raised cam portion, and thereafter as the driving member rotates the pawl will be permitted by said depression to contact with the small tooth for a short time and move the ratchet forward a sufficient distance to permit engagement of the pawl with the large tooth again, whereby the driven member is rotated intermittently.

85 90 95 100 105 4. A driving mechanism comprising a continuously rotated driving member, a driven member, a pawl connected to one and a ratchet to the other, said ratchet having a large tooth and several small teeth, a cam follower connected to the pawl, a movable cam having raised portions of different lengths capable of lifting the pawl from the large tooth as the follower rides thereover, a cam having a depressed portion in the path of the follower capable of permitting contact of the pawl with a small tooth, and means to adjust the cams so that the pawl will be removed periodically from engagement with the large tooth, said parts being so constructed and arranged that the pawl may revolve the large tooth through a single turn and then be removed therefrom, after which the pawl engages a small tooth and moves the ratchet forward a short distance, the lengths of the raised cam portions being such that the pawl may be held from engagement with the large tooth while the driving member rotates through one or more rotations.

110 115 120 125 5. A driving mechanism comprising a continuously rotatable driver, a driven member, a pawl and ratchet connection therebetween, a cam follower arranged to make and break said connection, a cam having a substantially circular outline concentric with the ratchet arranged to cause the pawl to revolve continuously in contact with the ratchet, a movable cam having an effective raised portion thereon, and means to move said movable cam to interpose said portion in the path of the cam follower to break the driving connection periodically or to withdraw it behind the other cam, whereby the driven member may remain still for an indefinite time or be rotated a single turn and then caused to stand substantially still while the driver makes a predetermined number of turns.

130 6. A driving mechanism comprising a continuously rotated driving member, a driven member, a ratchet having a large tooth and several small teeth connected with one of said members, a pawl operatively associated with

the ratchet and connected with the other of said members, and a cam device having a cam follower connected with said pawl and two relatively movable cam members, one having a substantially circular outline concentric with the ratchet and a depression therein, and the other cam having projections of different lengths arranged to be interposed in the path of the cam follower above the circular cam to remove the pawl from contact with the big tooth, and the depression in the cam being so located that the pawl may engage one of the small teeth and move it through a short distance and thereby move the ratchet ahead until the pawl will not be prevented from contacting with the large tooth, whereby the driven member may be rotated throughout a complete revolution and then permitted to remain substantially stationary while the driving member rotates one or more revolutions.

7. A driving mechanism comprising a driver, a driven member, a pawl and ratchet connection therebetween, a cam follower arranged to connect and disconnect the pawl from the ratchet, a cam to control said cam follower comprising two relatively adjustable parts, one serving to provide a dwell portion and the other having follower lifting portions of different lengths capable of holding the follower lifted for different time intervals, said follower lifting portions being movable successively from an ineffective position behind the dwell portion to an effective follower lifting position, and means for moving the cam and cam follower relatively so that the pawl may engage the ratchet and cause the driven member to rotate for a single turn after the driver has rotated through a predetermined number of turns as determined by the effective length of the follower lifting portion.

8. A driving mechanism comprising a rotatable driving member, a driven member, a releasable driving connection therebetween, means comprising a cam follower to release or make said driving connection, and a cam arranged to contact with the cam follower, said cam being constructed of two relatively adjustable parts, one having a dwell portion, and the other having a follower lifting portion movable to an ineffective position behind the dwell portion or to an effective follower lifting position.

9. A driving mechanism comprising a continuously rotatable driving member, a driven member, a releasable driving connection therebetween, a cam follower arranged to release or make said driving connection and rotatable with the driving member, and a cam arranged to contact with the cam follower, said cam being constructed of two parts, one of which is adjustable rotatably relative to the other about an axis spaced from the axis of the driving member and par-

allel thereto so as to vary the effective shape of the cam surface.

10. A driving mechanism comprising a continuously rotatable driving member, a driven member, a releasable driving connection therebetween, a cam follower arranged to release or make said driving connection and rotatable with the driving member, and a cam arranged to contact with the cam follower, said cam being constructed of two parts, one of which is stationary and the other of which is manually adjustable rotatably, during the operation of the mechanism, about an axis spaced from the axis of the driving member and parallel thereto so as to vary the effective shape of the cam surface.

11. A driving mechanism comprising a rotatable driving member, a rotary driven member, a releasable revolving pawl on one member and ratchet teeth on the other, a cam follower connected with the pawl to lift it from contact with the teeth and a cam arranged to control and operate the revolving follower, said cam being made of two relatively adjustable parts, one having a dwell portion and the other having a follower lifting portion movable to an ineffective position behind the dwell portion or to an effective follower lifting position, whereby the effective shape of the cam may be varied to cause the pawl to remain in contact with the teeth or to provide a projection on the cam sufficiently high to lift the pawl periodically out of contact with the ratchet teeth.
